UNITED STATES PATENT OFFICE.

JOSEPH H. COOPER, OF CHICAGO, ILLINOIS.

METHOD OF BURNING COMMINUTED FUEL.

1,397,266.

Specification of Letters Patent.

Patented Nov. 15, 1921.

Application filed July 20, 1918. Serial No. 245,802.

To all whom it may concern:

Be it known that I, JOSEPH H. COOPER, a citizen of the United States, residing in Chicago, in the county of Cook and State of Illinois, have invented certain new and useful Improvements in Methods of Burning Comminuted Fuel, of which the following is a specification.

This invention relates to the burning of comminuted fuel and has for its primary object the provision of an improved method of burning said fuel whereby the maximum heating efficiency is procured, whereby the fire-box or other fire containing chamber employed is protected from the gouging or blow torch effect of a flame confined in a narrow path and traveling at high velocity, whereby all volatile matter is gasified and all combustible matter burned within the fire-box, whereby all non-volatile and non-combustible matter is granulated within the fire-box, and whereby the fuel employed is with great thoroughness mixed with the air necessary to support its combustion.

While the method of this invention is adapted for the advantageous use of liquid fuel, they are more particularly intended for the consumption of pulverized fuels such as coal-dust.

Other objects and advantages of the invention will appear from the following description, taken in conjunction with the accompanying drawings which form a part of this specification and illustrate the preferred embodiment of the invention.

In the drawings:

Figure 1 is a vertical fragmentary section of a locomotive taken approximately on line 1—1 of Fig. 2.

Fig. 2 is a section taken approximately on line 2—2 of Fig. 1.

Fig. 3 is a section taken on line 3—3 of Fig. 1 and looking toward the front of the locomotive.

Fig. 4 is a section taken on line 4—4 of Fig. 1 and looking toward the rear of the locomotive.

Supported in any suitable manner (not shown) from the driving wheels 10 and 11 and cab supporting trailer wheels 12 through the medium of a frame 13 are the locomotive fire-box and boiler illustrated in the drawings. The flame flues for the boiler are shown at 14 projecting forwardly from the flue sheet 15 at the front end of the fire-box and within the boiler shell shown at

16. The crown sheet of the fire-box is indicated at 17, the bottom sheet at 18 and the back sheet at 19. The lower edges of the boiler shell 16 about the fire-box are secured 60 against the outer surface of the mud ring 20 as are also the lower edges of the flue sheet 15, back sheet 19, and side sheets 21 of the fire-box. Preferably the bottom sheet 18 of the fire-box is considerably below the mud 65 ring 20 and is connected thereto by upwardly and outwardly slanting sheets 22 and 23. The sheets 22 and 23 have their greatest vertical extent and highest pitch at the rear end of the fire-box and their upper edges 70 decline toward the forward end of the fire-box. These sheets join the horizontal bottom sheet 18 with the backwardly and upwardly slanting mud ring 20. At the rear of the fire-box a cinder hopper 24 having a 75 normally closed door 25 is secured below the bottom sheet 18 and receives granulated slag from the fire-box through an aperture 26. The bottom of the fire-box is interiorly sheathed with fire brick 27 up to approximately the plane of the upper surface of the mud ring 20, one of the objects of the present invention being that the flame developed can be safely permitted to strike directly 80 against the sheets of the fire-box which are 85 in contact on their opposite sides with the water and the steam in the boiler. The heating efficiency of the fuel burned is thereby increased inasmuch as there is no thick layer 90 of fire brick interposed between the flame and the water contacting sheets of the fire-box, and the heating of the water is facilitated. In central position in the front wall of the fire-box and at the bottom thereof an aperture 28 for injection of fuel is formed, 95 and a mixer casting 29 is bolted in any suitable manner to the mud ring 20 and bottom sheet 18 and has its horizontal mixing chamber 31 alined and in communication with aperture 28. Fuel feed pipe 32 conveys comminuted fuel suspended in air from the tender (not shown) along the exterior of the fire-box and across the front thereof to a point above the mixing chamber 31. The fuel from pipe 32 is blown downwardly into 100 the mixing chamber near the forward end thereof through an aperture 33 formed in its upper wall. In practice the amount of air employed in pipe 32 to convey the comminuted fuel from the tender to the mixing chamber is insufficient for complete combustion of the fuel. A portion of the addi- 105 110

- tional air necessary is conveyed through hot air flues 34 formed by securing an angular strip of steel horizontally to the exterior of the slanting bottom walls 22 and 23, through 5 an aperture 35 extending upwardly through the bottom wall of the mixing chamber 31 opposite aperture 33. Preferably the forward wall of aperture 35 stands slightly forward of the forward wall of aperture 33. 10 The rear ends of hot air flues 34 are each closed by a controlling door 36 hinged as at 37 to the bottom sheets 22 and 23 respectively. The remaining air additional for proper combustion is furnished cold to the 15 mixing chamber 31 from a rotary fan 40 and a cold air pipe 38 through a cold air injector 39 fitting the forward end of the casting 29 and having its rear face preferably flush with the forward wall of aperture 33 and 20 positioned consequently above the center of aperture 35; the rear tip of the injector 39 is also spaced slightly above the bottom wall of mixing chamber 31 in order that the cold air from fan 40 may, on the injector principle, draw hot air through flues 34 and aperture 35. In order that the cloud of fuel and air supplied through mixing chamber 31 may initially substantially fill the narrow bottom portion of the fire-box between the 25 lower edges of sheets 22 and 23, the mixing chamber is in cross section an elongated rectangle having its greatest dimension horizontal, and the cold air feed opening of injector 39 is similarly shaped and positioned 30 in cross section, while at the same time aperture 35 is substantially co-extensive from left to right with the width of the mixing chamber and the aperture 33 is centrally positioned in the top wall of the mixing chamber 35 but is considerably shorter than aperture 35. It will be seen that the hot air drawn from flues 34 is introduced into the bottom of the mixing chamber 31 and has the normal tendency of hot air to rise; that the 40 fuel laden air from pipe 32 is introduced into the top of the mixing chamber through an aperture shorter than that for the hot air, the fuel, being heavier than air, having a normal tendency to sink. The streams of 45 fuel laden air and hot air are so positioned therefore that advantage is taken of their physical characteristics, the one to sink and the other to rise, in order that the best possible mixture of these two currents may result. The hot air intake aperture being longer than that for the fuel, the hot air envelopes the incoming fuel just as the two streams of air enter the mixing chamber. It will be also noted that the necessary cold 50 air is fed into the mixing chamber between the opposite apertures 33 and 35, and at right angles to the direction of the flow of hot air and fuel entering the mixing chamber. The cold air from fan 40 is introduced 55 at a comparatively low velocity in order to

eliminate a blow torch effect of the flame upon the interior of the fire box, but its velocity is sufficient to draw hot air through flues 34 and to violently agitate the mixture of hot air and fuel constantly formed at the 70 forward end of the mixing chamber. The draft of fuel laden air through pipe 32 is purposely of low velocity, it being understood that the normal draft induced in every locomotive by reason of the exhaust from the 75 cylinders (not shown) is present in the fire-box. The velocities with which the fuel laden air and the cold air enter the mixing chamber may of course be varied by control of the draft through pipe 32 by any 80 of the ordinary means (not shown) and by increasing or decreasing the speed of rotation of fan 40. These fluctuations will be made in accordance with the requirements 85 of conditions, but the draft induced through the fire-box will at all times be sluggish and in accordance with the short flame principle 90 of consumption of comminuted fuel as distinguished from the violent draft provided on the long flame combustion principle in 95 such constructions as are employed in cement kilns and the like, where a narrow path of flame traveling at high velocity has a gouging blow torch effect upon any substance against which it is directed. 95

The present invention contemplates the production of a continuous but attenuated flame in the fire-box through which such a relatively sluggish draft passes as has just been mentioned. In order to give the flame 100 a long path of travel through the fire-box, the fuel is injected only at the forward end of the fire-box in the present invention and passes from mixing chamber 31, through aperture 28 and along the fire brick covering the bottom sheet 18, to the rear wall of the fire-box. Here it is turned forwardly and upwardly by a baffle arch 41 of fire brick traversing the rear portion of the fire box from side to side, slanting forwardly 110 and upwardly a comparatively short distance therein, and spaced above the bottom of the fire-box a sufficient distance to permit the combustible mixture already kindled to enter between it and the bottom of the box, and be turned in the direction indicated by the arrows in Fig. 1. As the flame passes forwardly beyond the front edge of arch 41 it is struck by a sheet of steam projected 115 against it from the whole front edge of arch 41 and directed forwardly and downwardly from a slot 42 in the forward side of a steam sheet pipe 43 which is fed from a steam feed pipe 44 that enters the arch preferably through the back sheet 19 of the fire-box. The effect of the steam sheet sprayed through aperture 42 is three-fold; it changes the direction of the flame to one substantially horizontal, gives added impetus to the 120 flame to project it against the flue sheet 125 130

15, and also spreads the flame horizontally across the whole area of the fire-box and against the side sheets 21. Under the influence of this steam sheet the flame strikes 5 the flue sheet 15 at a point indicated by numeral 45, being substantially horizontally opposite the forward edge of the baffle arch 41. From a position on the flue sheet just above the area indicated at 45, a smoke arch 10 46, supported on the customary arch tubes 47, projects backwardly and upwardly through the fire-box in order to deflect the flame backwardly before permitting it to pass to the flues 14 the rear openings of all 15 of which lie above the bottom of this arch 46. By introducing the flame at the forward end of the fire-box and the bottom thereof and deflecting it three times as shown by the arrows in Fig. 1, I so increase 20 its length as to allow time during its passage for the vaporization of all volatile matter, the complete burning of all combustible matter, and also the granulation of the large quantity of liquid slag formed 25 from the flame and which heretofore has in most instances been projected in liquid form against the flue sheet and into the flues, necessitating very frequently the cleaning off of the slag thus plastered on the flues 30 and flue sheet. A large portion of the granulated slag will drop to the bottom of the fire-box and be swept backwardly therein by the blast from the mixing chamber and will fall through aperture 26 into 35 the slag hopper 24. The remaining portion will be blown as cinders through the flues 14 and projected from the stack in cases where this invention is applied to locomotives. Attention is drawn to the fact that 40 the backward sweep of incoming fuel along the bottom of the fire-box constantly removes the granular slag formed. The attenuation of the flame, combined with the action of the steam sheet in spreading the flame throughout the fire-box and against 45 the side sheets, greatly increases the area of contact between the flame and the side sheets; the result is of course a better heating of the water in the boiler, and the fire- 50 box sheets themselves are longer-lived because of this distribution of the flame over a larger area and also because of the sluggishness of the draft, the consequent absence of any gouging effect from the flame, and the elimination of a large area of fire 55 brick from the lower portions of the fire- box sheets thus made permissible. It will be further seen that the cloud of fuel projected from the mixing chamber is not one 60 interiorly too rich in fuel and having only about its exterior sufficient additional air for proper combustion, but is one in which sufficient air for combustion is thoroughly mixed with the fuel laden air through the 65 cloud so that each fine particle of fuel is surrounded by an envelop of air sufficient for its complete combustion and the whole cloud of air is permeated and well heated by the thorough mixture within it of the hot air drawn through the flues 34. The fire- 70 box is tight and sufficient air for the proper combustion of the fuel admitted is constantly supplied with the fuel through the mixing chamber. Features of great utility result from this method in combination with 75 the length and sluggishness of the flame, one of these advantages is the reduction of the amount of smoke emitted from the fire- box as the result of complete combustion, the oxygen being highly heated in the fire- 80 box, and combining perfectly with the carbon in the fuel, thus eliminating the formation of CO; a further advantage lies in the fact that a locomotive or other heating plant equipped with the apparatus of this 85 invention and operating in accordance with its method, does not throw out partly burned cinders the combustion of which is continued on roofs and in fields where such cinders fall setting fire to objects along the 90 railroad right of way or in the locality of the heating plant; whatever hot cinders are emitted from the fire-box are composed of non-combustible, non-volatile matter, are rapidly cooled in the outer air, and contain 95 no unconsumed carbon whereby their kindling heat could be maintained after they have dropped to the ground.

Under varying conditions of steam pressure and grade of fuel, it will at times be 100 advisable to reduce the fluid pressure in pipe 44 to lessen the speed with which fluid is ejected from slot 42, and it will also at times be necessary to the most economical practice that a small proportion of air be admitted 105 to the flame through slot 42. For these reasons the rear end of pipe 44 is flared to form a frusto-conical mouth 50 within which is positioned a forwardly tapered steam nozzle 51, the latter being adjustable by any suitable 110 means (not shown) so that it may be moved axially of mouth 50 to increase or decrease the amount of air entering pipes 44 and 43 by the injector effect of the steam from the nozzle; or the nozzle 51 may be inserted 115 until it, contacts with the smaller end of mouth 50, so that the ingress or air is prevented and pure steam projected in a sheet from slot 42 instead of a mixture of steam and air.

I claim:

1. The herein described method of burning comminuted fuel, which consists in causing a flame from said fuel to travel the length of a fire-box four times between its 125 introduction and emission.
2. The herein described method of burning comminuted fuel, which consists in causing the flame from said fuel to travel the length of a fire-box four times between its 130

introduction and emission, and spreading said flame transversely throughout the fire-box.

3. The herein described method of burning comminuted fuel, which consists in projecting the flame from a combustible mixture of said fuel backwardly from the lower portion of a fire-box, deflecting upwardly and forwardly from the back of the fire-box
- 10 the flame from said fuel, projecting said flame subsequently against the front wall of the fire-box and spreading it against the side thereof, then deflecting the flame a second time backwardly and upwardly against
- 15 the back and crown sheets of the fire-box, and then causing said flame to travel forwardly beneath the crown sheet of the fire-box.

4. The herein described method of burning comminuted fuel, which consists in projecting the flame from a combustible mixture of said fuel backwardly from the lower forward portion of a fire-box, deflecting upwardly and forwardly from the back of the
- 20 fire-box the flame from said fuel, projecting said flame subsequently horizontally against the front wall of the fire-box and spreading it against the side sheets thereof, then deflecting the flame a second time backwardly
- 25 and upwardly against the back and crown sheets of the fire-box and then causing said flame to travel forwardly beneath the crown sheet of the fire-box.

5. The herein described method of burn-

ing comminuted fuel, which consists in projecting downwardly into the top of a mixing chamber a rich mixture of fuel and air, projecting oppositely into the bottom of said chamber a current of heated air greater in transverse extent than the said rich mixture

35 whereby the rich mixture is enveloped by the heated air, and igniting the mixture thus produced.

6. The herein described method of burning comminuted fuel, which consists in introducing downwardly into the top of a mixing chamber a rich mixture of fuel and air, projecting oppositely and upwardly into said chamber a current of heated air, projecting horizontally across said first named

40 current a draft of cold air, and igniting the mixture thus produced.

7. The herein described method of burning comminuted fuel, which consists in projecting into a mixing chamber a non-explosive rich mixture of fuel and air in a current having a given transverse dimension, projecting a draft of cold air against said current at right angles thereto and in a volume having its transverse dimension substantially

45 the same as that of said current, causing said draft of air to inject into the mixture thus produced a current of hot air having its transverse dimension greater than that of

50 said rich mixture and igniting the mixture

55 thus produced.

JOSEPH H. COOPER.
